US00D630419S

(12) **United States Design Patent**
Torrance et al.

(10) **Patent No.:** US D630,419 S
(45) **Date of Patent:** ** Jan. 11, 2011

(54) **BASE PLATE FOR ADJUSTABLE STRAP**

(75) Inventors: **Tony L. Torrance**, Boulder, CO (US);
Ian R. Moore, Loveland, CO (US)

(73) Assignee: **Dashamerica, Inc.**, Louisville, CO (US)

(**) Term: **14 Years**

(21) Appl. No.: **29/338,199**

(22) Filed: **Jun. 5, 2009**

(51) **LOC (9) Cl.** 02-04

(52) **U.S. Cl.** D2/946; D2/978

(58) **Field of Classification Search** D2/946,
D2/976, 978; 36/83, 136, 50.1–50.5
See application file for complete search history.

CLAIM

The ornamental design for a base plate for adjustable strap, as shown and described.

DESCRIPTION

FIG. 1 is a perspective view of the new adjustable strap design;

FIG. 2 is a top plan view of the invention illustrated in FIG. 1; FIG. 3 is a right side view of the invention illustrated in FIG. 1;

FIG. 4 is a left side view of the invention illustrated in FIG. 1; FIG. 5 is a bottom view of the invention illustrated in FIG. 1; FIG. 6 is a back plan view of the invention illustrated in FIG. 1;

FIG. 7 is a top view of the invention illustrated in FIG. 1;

FIG. 8 is a top plan view of the invention illustrated in FIG. 1 in relation to a strap, the broken lines showing environment for illustrative purposes only and forming no part of the claimed design in FIG. 1; and,

FIG. 9 is a right side view of the invention illustrated in FIG. 1 in relation to a strap, the broken lines showing environment for illustrative purposes only and forming no part of the claimed design in FIG. 1.
